SKATE WHEEL AND METHOD OF
PRODUCING SAME

Leland G. Knapp, Chicago, Ill., assignor to Montgomery Ward & Co., Incorporated, Chicago, Ill., a corporation of Illinois

Application April 3, 1933, Serial No. 664,145

6 Claims. (Cl. 208—181)

The primary object of the present invention is to improve the construction of wheels used with roller skates so as to render them more durable and lasting.

5 As now constructed, wheels employed for the purposes indicated wear out quickly. They are incapable of resisting the rough usage to which they are most commonly subjected, as when the user skates upon cement and concrete walks and 10 other surfaces offering high abrasive action to the wheels. In the general form and construction of skate wheels employed in the present-day skate only a relatively small quantity of metal is present in their rims. This is due to the fact 15 that the wheels are formed by stamping and bending, and the rims are constituted by overlapping layers which provide but little thickness. The outer layer, therefore, receives the direct wear and when this outer layer becomes 20 worn life of the wheel is gone. A new wheel must be substituted if the use of the skate is to be continued.

The present invention aims to provide a novel form of skate wheel by which the objections and 25 disadvantages above pointed out are overcome. It contemplates a wheel wherein the rim is formed of a single thickness of massed metal to provide the necessary wear-resisting properties to meet the rough usage to which the wheel is 30 subjected, thereby strengthening the wheel and imparting to the same greater durability and longevity.

A further object of the present invention is the provision of a wheel of the character referred to embodying in its construction such an arrangement and organization of parts as will 35 permit the same to be manufactured at relatively low cost, and thus enable its use in the low priced skates now found generally in commerce.

40 A further object of the invention is the provision of novel methods of manufacture by which the costs of production are reduced to the minimum, thereby contributing to the availability of the wheel for the general use to which the same 45 is adapted.

Other objects and advantages of the invention will appear as the nature of the improvements is better understood, the invention consisting substantially in the novel construction and combination of parts, together with the methods of manufacture, hereinafter fully described, illustrated in the accompanying drawing, and pointed out in the appended claims.

50 While the form of the invention herein shown and described, and the methods of its manufac-

ture herein delineated, are believed to be preferred embodiments thereof, it is to be understood that the same are susceptible of various changes in the form, proportion and minor details of the parts, and the steps of the methods, so that the present disclosure is to be considered from the illustrative standpoint rather than as imposing limitations on the invention.

In the drawing:

Fig. 1 is a side elevation of a skate wheel constructed in accordance with the present invention;

Fig. 2 is a vertical transverse sectional view thereof, on an enlarged scale, as on the line 2—2 of Fig. 1;

Fig. 3 is also a transverse sectional view of the wheel, the viewpoint being at right angles to that of Fig. 2, as on the line 3—3 of Fig. 2;

Fig. 4 is a disassociated sectional view of the components of the wheel, the balls being omitted.

Referring in detail to the drawing, the numeral 10 designates an elongated sleeve, which constitutes the hub of the herein described wheel. At the center of the sleeve 10 is located a collar 11, which is of integral formation with the sleeve. 25 The periphery of the collar 11 is formed with an inwardly tapering groove 12, and this groove receives a plurality of balls 13 which are adapted to travel therein, and constitute the anti-friction bearings of the wheel.

Arranged at either side of the collar 11 is a disk 14, these disks being of complementary form and construction, and jointly comprising the web of the wheel. Each of the disks 14 has a central opening 15, which is of sufficient diameter 35 to receive one end of the hub or sleeve 10 to permit the disks to freely rotate about said sleeve. Immediately adjacent to each of the openings 15 the body of each of the disks is curved inwardly to afford a contact area 16, the inner faces of the 40 latter bearing upon the balls 13, and thereby sustaining proper traveling contact between the disks and the balls. Preferably, the contact faces of the areas 16 lie at an angle of approximately 45° to the vertical axis of the wheel, thereby insuring a proper support by the balls of the disks.

In contiguous relation to the contact area 16 the bodies of the disks 14 extend outwardly or radially in straight lines to provide clamping areas 17 of substantial length. In the assembled relation of the disks the clamping areas 17 are parallel with each other and embrace and lie upon an inwardly extending rigid attaching flange 18 which is integral with and carried by the rim or tread 19 of the wheel. The length of 50 55

this flange 18 is substantially coextensive with that of the clamping areas 17, the faces of the flange 18 thereby providing extended surfaces of support for these areas upon which to anchor the disks 14.

To fasten the clamping areas 17 of the disks 14 to the flange 18 a series of rivets 20 is employed. These rivets extend through the flange 18 and the disks 14, and are upset in order to hold these parts in tight relation with respect to each other.

Each of the clamping areas 17 of the disks 14 terminates in an angularly disposed annular supporting flange 21, said flanges extending circumferentially of the disks 14, and being seated against the inner surface of the rim 19. The flanges 21 extend in divergent relation to each other, and thereby are projected in spaced relation to the flange 18 of the rim 19, so that in this positioning of the flanges 21 they afford support for the rim 19 at points intermediate of the flange 18 and the edges of the rim 19. Thus, the rim 19 is supported not only by the flange 18, through its engagement by the rivets 20 with the webs of the disks 14, but the flanges 21 of these disks tightly engage the rim 19, and thereby support this rim at the sides of the flange 18. A greatly strengthened rim for the wheel thereby is provided, and the edges of the rim are supported against bending strains.

A closure cap 22 is provided for the wheel at the openings 15 of the disks 14. These caps are formed of sheet metal, the bodies thereof being dished so that the free edges rest upon the bowed contact areas 16 in frictional engagement therewith. At the center of each of the caps 22 is an outwardly extending hub 23 formed with an inwardly extending flange 24 that projects at right angles to the hub 23. The flanges 24 abut against the ends of the sleeve 10, and provide openings at the centers of the closure caps 22 which receive the axle 25 of the wheel. It will be understood that the axle 25 is carried by the supporting bracket 26 of the body of the skate, the axle 25 being of sufficient length to carry at each of its ends one of the wheels in the usual manner. The axle 25 is provided with a head (not shown) at one of its ends, and a fastening nut 27 at its other end. When, therefore, the wheels are assembled in coupled relation on the axle 25 the tightening of the nut 27 to the desired extent will bind the axle 25 in stationary relation to the supporting bracket 26, and this likewise holds the sleeve 10 against rotation. The inner cap 22 being interposed between the supporting bracket 26 and the inner end of the sleeve 10, and the outer cap 22 being likewise interposed between the outer end of the sleeve 10 and the nut 27, a washer 28 being arranged between the latter and the outer cap, the closure caps likewise are held in tight relation with respect to the sleeve 10 and do not rotate.

From the foregoing description it is apparent that the rim 19 of the wheel is of a single thickness of massed metal, which thickness may be increased or diminished to the desired extent, but of such degree of thickness as to afford high-resisting capacity to the rough surfaces over which the wheel usually travels in the ordinary usage to which roller skates are subjected. In the wear exerted on the rim 19 the entire mass of the metal therein responds thereto, and even though the entire thickness of the rim may be worn away, and thereby expose the flanges 21, these flanges still will serve as a rim for the wheel,

and as a bearing surface with which to contact the roadway over which the wheel is traveling. Moreover, by employing the flanges 21, the inner side of the rim 19 is trussed against bending strains, and a solid structure is afforded in the assembled relation between the webs 14 in their engagement with the flange 18, and the contact of the flanges 21 with the rim 19. In this connection it is also observed that the diameter of each of the disks 14 is slightly greater than the diameter or distance of the space between the inner faces of the rim 19, and due to this, when the wheel is assembled, the disks 14 must be forced under pressure against the flange 18 into the position which they occupy in the assembled relation of the parts. This adds to the strength of the entire wheel structure.

In forming the herein described wheel the rim 19 with its supporting flange 18 is produced from a suitable sized body of metal heated to the desired degree, and subjected to the action of suitably formed forging dies. In this step the metal is manipulated by the dies so as to produce the flange 18 in its inwardly extended relation to the rim 19, the required amount of metal being massed in the rim to impart thereto the required thickness. Simultaneously with the formation of the flange 18 the centrally disposed opening formed by this flange is produced. The disks 14 are stamped to the configuration which they assume, and the closure caps 22 likewise are formed by stamping.

With the rim 19 and its supporting flange 18 thus produced, together with the disks 14 and the closure caps 22, the parts are assembled with the sleeve 10 upon the axle 25, one of the disks 14 being applied to the sleeve 10, whereupon the balls 13 are positioned in the runway or groove 12, and after this has been accomplished the other disk 14 is positioned within the rim 19, the rivets 20 completing the fastening of the disks to the supporting flange 18. The wheel is then ready for positioning on the axle, and for application of the closure caps 22 to the structure.

As an alternative method for the production of the rim of the wheel, the rim 19 may comprise an appropriate length or section of a tube, the walls of which are of the required thickness to impart the thickness desired for the rim 19. The supporting flange 18 may comprise a centrally perforated disk of a diameter to fit within the rim 19. The disk thus selected is introduced to the inside of the rim 19 at the central portion thereof between the edges of the rim, and the rim 19 and the disk subjected to a welding heat of sufficient degree to fuse the disk and the rim together. In such fused relation the flange 18 becomes integral with the rim 19, and the solidified structure of these parts as illustrated in Fig. 2 results. After the rim and the flange have been brought together in the manner just described the other parts of the wheel are assembled with respect to the rim and its flange in the manner above indicated as when the rim 19 and its flange 18 are formed by forging.

The present invention sharply distinguishes from the construction of skate wheel now commonly employed because of the single thickness of the rim 19 which, by such single thickness, masses the metal in the rim. The wear is received by this massed metal, and because of the thickness of the same it is obvious that there is greater durability and longevity to the wheel, with greater wear-resisting properties to meet the rough usage to which the wheel is subjected.

In producing the herein described wheel structure the rim 19 is pack hardened or case hardened so as to further increase its wear-resisting properties without rendering the same of such brittleness as to break under the wear to which it is subjected. The disks 14 are also hardened to increase their strength. Preferably, this is effected by cyanide hardening.

I claim:

- 10 1. In a wheel of the class described, the combination with an integral rim of required thickness for resisting the wear to which the same is subjected, and an inwardly extending rigid attaching flange arranged at the inner face of the 15 rim and integral with the latter, of a plurality of disks arranged within the rim and disposed at opposite sides of said flange, said disks embracing and lying upon said flange, each of said disks being provided with a peripheral flange seated 20 against the inner face of the rim, whereby to support the latter at the sides of said inwardly extending flange, and means for connecting said inwardly extending flange of the rim and said disks.
- 25 2. In a wheel of the class described, the combination with an integral rim of required thickness for resisting the wear to which the same is subjected, and an inwardly extending rigid attaching flange arranged at the inner face of the 30 rim and integral with the latter, of a plurality of disks arranged within the rim and disposed at opposite sides of said flange, said disks embracing and lying upon said flange, each of said disks being provided with a peripheral flange 35 extending at an angle to the disk and seated against the inner face of the rim, whereby to support the latter at the sides of said inwardly extending flange, and means for connecting said inwardly extending flange of the rim and said disks.
- 40 3. In a wheel of the class described, the combination with an integral rim of required thickness for resisting the wear to which the same is subjected, and an inwardly extending rigid attaching flange arranged at the inner face of the 45 rim and integral with the latter, of a plurality of disks arranged within the rim and disposed at opposite sides of said flange, said disks embracing and lying upon said flange, each of said disks being provided with a peripheral flange seated 50 against the inner face of the rim, whereby to support the latter at the sides of said inwardly extending flange, the diameter of each of said disks being slightly greater than the internal diameter of said rim, thereby requiring the disks to be forced under pressure against the flange of the 55 rim into the position occupied by the disks in the assembled relation of the parts, and means for connecting said flange of the rim and said disks.

4. In a wheel of the class described, the combination with an integral tread, and an inwardly-extending rigid attaching flange arranged at the inner face of the tread and integral with the latter, of a pair of disks arranged within the tread 5 at opposite sides of said flange and constituting the web of the wheel, the bodies of said disks including radially-extending parallel clamping areas of substantial length which embrace and lie upon said flange, the latter being substantially coextensive in length with that of the clamping areas, whereby the faces of said flange provide extended surfaces of support for said clamping areas upon which to anchor said disks, and means for connecting the clamping areas of 15 the disks with said attaching flange.

5. In a wheel of the class described, the combination with an integral tread, and an inwardly-extending rigid attaching flange arranged at the inner face of the tread and integral with the latter, of a pair of disks arranged within the tread 20 at opposite sides of said flange and constituting the web of the wheel, the bodies of said disks including radially-extending parallel clamping areas of substantial length which embrace and lie upon said flange, the latter being substantially coextensive in length with that of the clamping areas, whereby the faces of said flange provide extended surfaces of support for 25 said clamping areas upon which to anchor said disks, each of said disks also being provided with a peripheral flange extending at an angle to the disk and seated against the inner face of the tread to support the tread at the sides of the inwardly-extending flange, and means for connecting 30 the clamping areas of the disks with said attaching flange.

6. In a wheel of the class described, the combination with an integral rim of required thickness for resisting the wear to which the same is 40 subjected, and an inwardly-extending rigid attaching flange arranged at the inner face of the rim and integral with the latter, of a plurality of disks arranged within the rim and disposed at opposite sides of said flange, said disks embracing and lying upon said flange, each of said disks being provided with a peripheral flange seated 45 against the inner face of the rim, whereby to support the latter at the sides of said inwardly-extending flange, the diameter of each of said disks being slightly greater than the internal diameter of said rim, thereby requiring the disks to be forced under pressure against the flange of the rim into the position occupied by the disks in the assembled relation of the parts, and means 50 for connecting said flange of the rim and said disks.

LELAND G. KNAPP.
